M. A. WICKS.

THERMOSTAT.

APPLICATION FILED JUNE 14, 1920.

Patented Sept. 19, 1922.

Inventor
Maurice A. Wicks

By Hull, Smith, Buck & West.

Attest.

Patented Sept. 19, 1922.

UNITED STATES PATENT OFFICE.

MAURICE A. WICKS, OF DETROIT, MICHIGAN, ASSIGNOR TO KELVINATOR CORPORATION, OF DETROIT, MICHIGAN, A CORPORATION OF DELAWARE.

THERMOSTAT.

Application filed June 14, 1920. Serial No. 388,832.

To all whom it may concern:

Be it known that I, MAURICE A. WICKS, a citizen of the United States, residing at Detroit, in the county of Wayne and State of Michigan, have invented a certain new and useful Improvement in Thermostats, of which the following is a full, clear, and exact description, reference being had to the accompanying drawings.

10. This invention relates to thermally controlled electric switches and is capable of many uses but is especially designed for use in connection with a refrigerating apparatus and has for its objects to provide an improved device in which an electric switch is controlled by temperature conditions in the apparatus, this switch in turn controlling an electric motor which drives the compressor of the apparatus and is started or stopped according to predetermined conditions. The objects of the invention are the provision of a simple and compact device which while small in total size shall possess a comparatively large operating chamber, a 15 large volume of volatile agent, a large exposed surface and a construction which shall shield the operating parts from injury either by external shocks or by internal pressure conditions due to excessive or deficient temperature. Other objects are the provision of a device which can be easily and simply manufactured and adjusted and which shall serve to break a current of considerable size without arcing and without necessitating the use of a relay; while further objects and advantages of the invention will become apparent as the description proceeds.

In the drawings accompanying and forming a part of this application I have illustrated one of the many physical structures in which my inventive idea can be embodied although without intent to limit myself to the particular designs and arrangements therein shown. Fig. 1 is a top plan view of my improved thermostat with the switch-box cover removed; Fig. 2 is a vertical sectional view of my improved thermostat; and Fig. 3 is a sectional view taken on the line 3-3 of Fig. 2 and looking in the direction 50 of the arrows.

Describing the parts by reference characters, 1 represents a circular supporting cap preferably having at its margin a rounded helical flange 2 in order that the device may 55 rest snugly upon the top of a coiled pipe.

Seated on the upper face of this cap and held thereto in any suitable manner as by screws 3-3 is the switch box 4 here shown as having a removable cover 5 and a flexible cable 6. Located inside this box is suitable switch mechanism adapted to be actuated by the reciprocation of the rod 7. The particular nature of the construction of the switch mechanism is not important, that shown herein being of the spring toggle type. The arrangement is such that upon the upward movement of the rod 7 the switch will be closed and the motor started, while upon the downward movement the switch will be opened and the motor stopped.

The rod 7 depends through a hole 10 formed in the cap and surrounded on the lower side by a depending cylindrical wall 11 which external surface is threaded for the reception of the adjusting ring 12. Also depending from the cap outside of this ring are a plurality of tension rods or bolts 13-13 to whose further ends is attached the end plate 14. Upon this plate is seated the expansible vessel 15, preferably made with longitudinally expansible, circumferentially corrugated, flexible sheet metal walls, and rigid end walls 16 and 17. The former is provided with a filling valve 18 and the latter with a connection adjustably secured to the rod 7. The end wall 17 is provided with a circular seat 20 and the ring 12 with a circular seat 21 which receive the ends of the compression spring 22 where by expansion of the flexible vessel is opposed; while the exterior of the ring 12 is formed with spanner openings 24 by means of which the same may be turned as is necessary to adjust the device for different 90 temperatures.

It will be noted that actuation of the switch always occurs at the same point of expansion or contraction of the flexible vessel so that the only condition required to be met for such operation is that of the temperature which determines the internal pressure of the vapor contained therein. It will also be noted that the number of parts, both movable and immovable, is very small, 105 and that these are symmetrically arranged resulting in a minimum tendency to bind or get out of order. It will be observed that the end of the wall 11 constitutes a stop for the expansible vessel and prevents 110

undue expansion thereof in case of unduly high temperatures. The device is adjusted so that the switch is actuated just before the vessel reaches this point. It will be understood, also, that many changes in detail can be made, and that I do not limit myself in any wise except as defined in the claims hereto annexed.

Having thus described my invention, what

10 I claim is:—

- 15 1. The combination with a supporting member having a hole, a depending threaded flange surrounding said hole, and an abutment ring adjustable along said threads, of an operating device projecting through said hole, an expansible metal vessel operatively engaging said device, a spring surrounding said flange and operatively engaging said abutment and opposing the expansion of the vessel, and means securing the further end of said vessel to said supporting member.
- 20 2. In a thermostat, in combination, a supporting member having on one side an externally threaded wall and an abutment ring adjustable therealong, an expansible metal vessel coaxial with said wall, a plurality of tension members carried by said member outside of said wall and attached to the
- 25 30 further end of the vessel, a spring inter-

posed between the vessel and ring, and a controlling device operatively attached to said vessel and adapted to be actuated before the expansion of the vessel brings it into engagement with said wall.

3. In a thermostat, in combination, an apertured supporting plate, a threaded flange projecting from said plate on one side and surrounding the aperture, a switch secured to the opposite side of said plate and overhanging said aperture, a longitudinally expansible, circumferentially-corrugated, cylindrical metal vessel supported in line with said aperture and having its further end secured at a fixed distance from said plate, the nearer end of said vessel being movable toward and from said plate through a distance which is limited by the end of said flange, an operating rod traversing said aperture and connecting said switch and vessel, a spring surrounding said flange and having one end bearing against the nearer end of said vessel, and a threaded adjusting member screwed to said threads and supporting the opposite end of said spring.

In testimony whereof I hereunto affix my signature.

MAURICE A. WICKS.
